PLATE 2.

Lyman N. Hopper's Design for Stove State.

Ms. 378

To S. Hapgood, Boston, Mass.

Letters Patent No. 378. Dated June 3, 1851

The Schedule which is in these letters Patent will make part of the same.

To all Persons to whom these Presents shall come:

Be it known, that

Lyman S. Hapgood of Boston, in the County of Suffolk and State of Massachusetts, have produced a new and original design for the top and front plates of a parlor stove, and I do hereby declare that the said new design is fully described and represented in the following specification and accompanying drawings, to which reference is herein after made.

The figures of the accompanying plates of drawings represent my new design. In plate 1, fig. 1 is a plan of the top plate and fig. 2 is a vertical section of the same taken in the plane of the line A B fig. 1.

In plate 2, fig. 3 is an elevation of the front plate, fig. 4 a section of the same taken in the plane of the line C D fig. 3, and fig. 5, is a section taken in the plane of the line E' F.

The top plate is of the shape shown in figs. 1 & 2 plate 1 and has around its edge the several mouldings a, b, c, d, e, leaving the plain flat space or panel f, g, h between these and the mouldings i, j, k, after which are the flat space or panel l, the plain mouldings or steps m, n & o, and the large panel p, q.

The front plate is of the shape shown in the figures of plate 2 and has around its outer edge the raised mouldings or steps m, n & o, and the moulding p, between which and a similar moulding q is the narrow space or panel r extending around the plate. Running across the centre of the plate is the triangular opening s, s. The main portion of this plate is ornamented with two series of gothic arches, divided by the triangular opening s, s before referred to, and formed by the mouldings or steps like those at m, n & o, enclosing the sunken panels o, o, &c. In each of these panels is the spear head t, t. Between each of the gothic arches, is a curved sunken panel x, x &c. formed by mouldings or steps m, n & o.

Having thus described my new design I shall state my claim as follows.

What I claim as my production and desire to have secured to me by Letters Patent is, the design consisting of the mouldings, panels and gothic arches herein
